United States Patent Office

Des. 192,583
Patented Apr. 10, 1962

192,583

AIRPLANE

Howell L. Walker, Los Angeles, Calif. (728 33rd St., Manhattan Beach, Calif.), and Raymond A. Young, Los Angeles, Calif. (22380 Cass Ave., Woodland Hills, Calif.)

Filed Mar. 16, 1961, Ser. No. 64,329

Term of patent 14 years

(Cl. D71—1)

Fig. 1

Fig. 2

Fig. 3

FIG. 4.

FIG. 1 is a perspective view illustrating the front, top and one side of an airplane embodying our new design, with the ducts in position for vertical take off;

FIGS. 2 and 3 are front and side elevations respectively, thereof, with the ducts in position for horizontal flight; and

FIG. 4 is a bottom plan view thereof as shown in FIGS. 2 and 3.

The undisclosed side of the airplane is substantially the same in appearance as the side shown.

We claim:

The ornamental design for an airplane, substantially as shown and described.
